UNITED STATES PATENT OFFICE.

WILLIAM C. BRINTON, JR., OF KENNETT SQUARE, PENNSYLVANIA, ASSIGNOR, BY
MESNE ASSIGNMENTS, TO PHILBRIN CORPORATION, OF KENNETT SQUARE, PENN-
SYLVANIA, A CORPORATION OF DELAWARE.

MEANS FOR INCREASING THE DIELECTRIC STRENGTH OF CONDENSERS.

1,414,619.

Specification of Letters Patent.

Patented May 2, 1922.

Application filed October 17, 1918. Serial No. 258,582.

To all whom it may concern:

Be it known that I, WILLIAM C. BRINTON, Jr., a citizen of the United States, residing at Kennett Square, county of Chester, and State of Pennsylvania, have invented a new and useful Improvement in Means for Increasing the Dielectric Strength of Condensers, of which the following is a full, clear, and exact description, reference being had 10 to the accompanying drawings, which form a part of this specification.

In ignition systems for internal combustion engines, in wireless telegraphy, and in many other situations, the provision of condensers which will resist all conditions, normal and abnormal, tending to break them down, has seemed to present an insoluble problem. The provision of a condenser which will stand up under all normal conditions is in itself a task of great difficulty, but even if such a condenser be provided, there are certain abnormal conditions which will break down an absolutely perfect condenser. The chief of these abnormal conditions is the breakage, accidental or deliberate, of the secondary circuit. Accidental breakage of the secondary circuit cannot always be avoided, although careful workmanship minimizes the risk. No well 20 trained engineer will deliberately open the secondary circuit: but electrically controlled apparatus is frequently operated by comparatively ill-trained or ignorant operators; the opening of the secondary circuit affords 30 a convenient means, for example, for slowing down an internal combustion engine; or it may be, and frequently is, opened experimentally to determine how the engine will operate under such conditions.

In the normal operation, for example, of an ignition system, the secondary circuit is induced by the opening of the primary circuit, the primary circuit being repeatedly rapidly opened and closed by means of a 40 vibrator or a contact maker and interrupter. The self-induction produced by the opening of the primary circuit raises its voltage and when the primary circuit is closed, the condenser impresses its high voltage upon the 50 primary circuit. If the secondary circuit remains broken, the resulting mounting voltage in the secondary coil causes the voltage of the primary circuit to rapidly increase far above normal, imposing a strain upon

the condenser far beyond that which it is 55 designed to resist. Hence, even though the condenser be absolutely perfect in its construction, with a reasonable margin of safety in the way of capacity and dielectric strength, it breaks down under the extraor- 60 dinary strain. The breaking down of the condenser paralyzes the whole system and may often produce the most serious results.

The danger exists to its maximum extent when the voltage rises rapidly. An efficient 65 condenser can stand an actually abnormal voltage provided the increase in voltage is gradual, but not if the increase is sudden.

I have solved the problem of building up the dielectric strength of a condenser so that 70 it will not break down even when the increase in voltage, from whatever cause, is both abnormal and sudden, by an expedient which is not only quite simple, but which involves no increase in the capacity of the condenser 75 and no change in the method of its manufacture. My invention, however, has been experimentally developed, and practically utilized, only with condensers of a specific type, and these may or may not be essential 80 to secure satisfactory results. Briefly, the invention presents the following characteristics. A plurality of condensers, preferably two, are arranged in the condenser circuit. They must be arranged in parallel and 85 not in series. They must be of different capacities. Their total capacity need only be the same as the calculated capacity of a single condenser adapted to meet normal conditions.

The accompanying drawing is a diagram showing the application of the invention to the ignition system of an internal combustion engine, although it will be understood that this is only one of many possible applications.

A source of current supply, *a*, which may be assumed to be a storage battery, is grounded at one side, while its other side is connected to the primary winding *b* of an 100 induction coil. The winding *b* connects with a contact maker and interrupter *c* actuated from an engine-driven shaft *d*. The secondary winding *e* of the induction coil is grounded at one side, while its other side is 105 connected to a distributor *f*, the rotating blade *g* of which (driven from shaft *d*) closes the secondary circuit successively

through the spark plugs of a plurality of engine cylinders, one cylinder h and spark plug i being shown. I prefer that the contact maker and interrupter shall have the 5 specific construction shown in the Brown and Brinton Patent No. 1,234,278, issued July 24, 1917. The distributor may be constructed in accordance with Brinton Patent, No. 1,227,109, issued May 22, 1917.

10 In the primary circuit, in shunt with the contact maker and interrupter, are two condensers m and n , arranged in parallel. These condensers are shown as of different size as a diagrammatic way of illustrating 15 their different capacities. If the two condensers are of precisely the same capacity, they are apparently no improvement over a single condenser. I have not determined, with absolute accuracy, what percentage of 20 variation in capacity is a prerequisite to success, but I have tried condensers whose respective capacities vary as little as two per cent and have found that they broke down, under conditions producing a sudden 25 mounting of voltage, about as quickly as a single condenser, while if the variation in capacity is increased to eight per cent the condensers will stand up under conditions which are invariably fatal where a single 30 condenser, or its equivalents—a plurality of condensers in series or a plurality of condensers of the same capacity in parallel—are used.

The observed phenomena in the case of a 35 sudden increase in voltage with the use of a single condenser is, first, violent sparking and then, or perhaps simultaneously, the burning of the condenser, thus destroying its properties. Where my invention is employed, there is no sparking, and the condensers are not deleteriously affected, but 40 take care of the highest voltage which can be created by the deliberate breaking of the secondary circuit. As above stated, I have 45 found it unnecessary to increase the total capacity of the two condensers beyond that which is required for a single condenser that is designed for normal working conditions.

50 The condensers that I have successfully employed are constructed in accordance with the Brinton Patent No. 1,237,015, issued August 14, 1917; and also embody the specific improvements set forth in my applications, Serial No. 181,735, filed July 20, 1917, and Serial No. 206,900, filed December 13, 1917.

55 My theory of the electrical action that

accounts for the ability of a pair of parallel unbalanced condensers to withstand a far 60 greater and more sudden increase of voltage than a single condenser of greater capacity is that there occurs a surging of the current back and forth from one condenser to another, each condenser momentarily taking 65 up the shock while the dielectric strength of the other is building up. I do not feel warranted, however, in advancing too confidently any scientific theory to account for the observed result. The precise action may 70 be too obscure to be with certainty discoverable. However, this exact knowledge is unnecessary to the practice of the invention, it being only necessary to follow the simple instructions herein contained to avoid the 75 breaking down heretofore deemed to be an inevitable consequence of a sudden marked increased in voltage.

Having now fully described my invention, what I claim and desire to protect by Letters Patent is:

1. The combination of a primary and a secondary circuit having an induction coil connected thereto, a make and break device, and a plurality of condensers of different 85 capacities connected in multiple to each other in the primary circuit.

2. An ignition system for internal combustion engines having an induction coil, a primary circuit connected in series with a 90 source of electrical energy, the primary winding of the induction coil and an interrupter, a secondary circuit connecting the secondary winding of the induction coil, a distributor and a spark plug in series, and 95 a condenser having a plurality of units of substantially different capacities connected in parallel with each other and shunting the interrupter.

3. An ignition system for combustion engines comprising an induction coil having a primary winding and a secondary winding, a source of electric energy, an interrupter, a plurality of condensers of different capacities, a distributor, a spark plug, a secondary 105 circuit connecting the secondary winding of the induction coil, the distributor and spark plug in series with each other, and a primary circuit connecting the condensers and interrupter in multiple with each other and 110 in series with the primary winding of the induction coil and the source of energy.

In testimony of which invention, I have hereunto set my hand, at Kennett Square, Pa., on this eleventh day of October, 1918.

115 WILLIAM C. BRINTON, JR.
